(57) **CLAIM**

The ornamental design for a display screen or portion thereof with graphical user interface, as shown and described.

DESCRIPTION

1. Display screen or portion thereof with graphical user interface

1.0 : Front

The outer perimeter, illustrated in the figures by a pair of broken lines, illustrates a display screen or portion thereof and forms no part of the claimed design. The remaining broken lines in the drawings illustrate portions of the graphical user interface that form no part of the claimed design.

(Continued)

The do-dash broken lines define boundaries of the claimed design and form no part thereof.
